UNITED STATES PATENT OFFICE.

GUY F. JONTZ, OF CLINTON, IOWA.

TOY.

Application filed January 16, 1925. Serial No. 2,743.

To all whom it may concern:

Be it known that I, GUY F. JONTZ, a citizen of the United States, and a resident of Clinton, Clinton County, and State of Iowa, have invented certain new and useful Improvements in Toys, of which the following is declared to be a full, clear, and exact description.

This invention relates to toys, and more particularly, to that class of toys that employ an endless revolvable track and a motor driven vehicle that travels thereon.

This invention is in the nature of an improvement on the type of toy shown and described in my pending application for patent, filed March 10, 1924, Serial No. 698,202, and its principal object is to provide an endless track of improved construction and arrangement, whereby the motor driven vehicle may run on it while suspended from its axis, in a vertical plane, or in a horizontal plane, or whether standing or lying on a flat horizontal surface such as a table, desk, sidewalk or the like. Another object is to provide an endless track structure, formed of two similar or complementary track members, each of which by itself, may act as an endless track for the vehicle, to travel on, and when bolted or otherwise secured together may support the vehicle in the various ways above set forth. Another object is to provide a track structure that may be conveniently formed of sheet metal, or bars, struck up or rolled to give the proper shape of track structure.

Another object is to provide means whereby the traction wheels of the vehicle may be employed to rotate the track structure while the vehicle is held stationary, or while it is free to run on the track. Other objects and advantages will appear in the following specification and with all of said objects and advantages in view, this invention consists in the several novel features hereinafter fully set forth and claimed.

The invention is clearly illustrated in the accompanying drawings, in which:—

Fig. 1 is a front elevation of a toy embodying the preferred form of the present invention; Fig. 2 is a side elevation thereof; Fig. 3 is a side elevation showing the track support and track placed in a horizontal position; Fig. 4 is a side elevation of the track structure disconnected from the support and showing another manner in which the toy may be used; Fig. 5 is a vertical

cross section of a fragment of the device, showing the track structure suspended upon the wheels of the vehicle; Fig. 6 is a detail, front elevation of a fragment of the track structure; Fig. 7 is a detail section taken on line 7—7 of Fig. 6; Fig. 8 is a detail cross section taken on line 8—8 of Fig. 6; Fig. 9 is a detail cross section taken on line 9—9 of Fig. 6; Fig. 10 is a detail cross section of a modified form of track structure; Fig. 11 is a detail cross section of a second modification; Fig. 12 is a detail cross section of a third modification; Fig. 13 is a detail cross section of a fourth modification and Fig. 14 is a detail cross section of the track structure illustrating a third rail member.

Referring first to Figs. 1 to 9 inclusive, which illustrate the preferred embodiment of the invention, the reference character A, designates a stand or supporting member, B a wheel containing the endless track structure, and capable of being rotatively mounted on said support, and also capable of rolling along a horizontal surface, and C designates a motor driven vehicle such as a toy locomotive, automobile or the like, which is arranged to travel on the rails of said track structure.

The supporting member A, comprises, in its simplest form, a base a , and a post or standard a^1 secured thereto approximately midway between its ends and near one edge. Projecting from said standard a^1 is a spindle a^2 upon which the wheel B may be rotatively mounted. The supporting member A may stand on its base a , (see Figs. 1 and 2) and it may be laid down upon a table, desk or the like (see Fig. 3). In either position its spindle a^2 is capable of rotatively supporting the wheel B.

In its preferred form the track structure comprises two similar, companion track members 15, 15, which are annular in form, and under certain circumstances are bolted or otherwise secured together. Each track member is struck up from sheet metal to provide a channel like ring having a flat web portion 16 and two annular concentric flanges 17, 17¹, the one flange 17¹ being within the confines of the flange 17. The flanges 17, 17¹ of one track member form a pair of rails for receiving the traction wheels C of the vehicle C when the track member is laid on its side.

The web portion 16 of each track member is struck up to form laterally distended

spacers or struts 18 which are spaced equidistant about the track member. Said spacers or struts project from the side of the web 16 opposite the one from which the flanges 17, 17¹ project. In assembling the track structure the track members 15 are placed back to back with the spacers in contact and then locked or otherwise secured together, bolts and nuts 19 being here shown for that purpose. The bolts pass through bolt holes in the spacers, and the nuts are turned up tight on the bolts to fasten the two track members together. When the track members are secured together, the two opposite flanges 17, 17, form a pair of rails for supporting the vehicle on the outer side of the wheel, (see Fig. 1) and the two opposite flanges 17¹, 17¹, form another pair of rails for supporting the vehicle on the inner side of the vehicle (see Fig. 4). It will be observed that the arrangement of the flanges 17, 17¹ is such that they will receive the wheels of the vehicle, whether the latter is placed on either side of the wheel, on its outer annular face or on its inner annular face. This arrangement permits the wheel to be used in the following several ways.

Each separate track member 15 may be laid on a table or the like with its flanges projecting upward, and the vehicle may be placed on its flanges 17, 17¹. The two track members may be fastened together and set on edge (see Fig. 4) and the vehicle may be set on the inner flanges 17¹, 17¹. The vehicle C contains a spring motor c¹, which is wound up with a key as is well understood, and when the spring is wound, the vehicle may be placed on the inner track (formed by the flanges 17¹, 17¹) and when released the tractive effect of the wheels of the vehicle is to propel the wheel B along the surface upon which it rests.

The vehicle C may, however, be secured to the standard a¹ in an inverted position (see Fig. 5) and the wheel B placed on the traction wheels of the vehicle. In this position the traction wheels rotate the wheel B. The means for supporting the vehicle in inverted position on the standard may comprise a U shaped pin 20, which is secured on the standard a¹ by pins 21 that may be inserted transversely through holes in the standard, one above and one below the U pin 20. The U pin is inserted through holes c² formed in the vehicle and supports it in inverted position. The means just described for supporting the vehicle in inverted position may, of course, be varied considerably but serves merely for the purpose of illustrating the invention.

For rotatively mounting the wheel upon the standard, spokes 22 are provided on the wheel, and a hub 23 is provided at the inner ends of the spokes. The spokes have laterally bent end portions 22¹ (see Fig. 9) which

extend through the webs of the two track members, and are secured thereon by nuts 22². Their other ends are secured in the hub 23. Said hub is preferably provided with ball bearings 24 to reduce friction to a minimum, and the inner ball bearing member is formed with a central hole that fits the spindle a². A cotter pin secured in the spindle secures the hub thereon.

When the wheel B is mounted on the spindle a², the vehicle C may be placed on the inner track, formed by the flanges 17¹, 17¹, and when its traction wheels rotate, they rotate the wheel upon the spindle. The vehicle may, however, be placed on top of the wheel (see Figs. 1 and 2) and secured to the standard a¹ by a pin 25, which is thrust through a hole in the vehicle and a hole in the standard. In this position the vehicle is held stationary on top of the wheel and its traction wheels rotate the wheel B upon the spindle.

The supporting member A, may, however, be laid down and the vehicle placed on the track formed by the flanges 17, 17¹ of the upper track member. In this position the vehicle runs forward and rotates the wheel in the reverse direction. By inserting the pin 25 through the base a, and locking the vehicle to the base, the bodily movement of the vehicle is arrested and the traction wheels thereupon rotate the wheel upon the spindle. By removing the pin 25 and inserting it in the base in position to engage the struts of the wheel, (see dotted lines Fig. 3) or by inserting it in the standard, in position to engage any of the spokes of the wheel, movement of the wheel is arrested, and the vehicle travels around on the upper track thereof.

The track structure may be formed in many ways, other than that illustrated in connection with the preferred form of the invention. The following are illustrations of such modifications.

In Fig. 10, in place of shearing the metal, to form the spacers or struts, the metal of the web is depressed by a suitable die to form the spacer 18^a. If desired washers 30 or other spacing means may be placed between the depressed parts to adjust the width of the track if desired.

In Fig. 11, outer and inner annular track members 15^b, 15^c are shown. Said track members may be rolled out of strips of metal to the cross section shown and secured together one within the other.

In Fig. 12, additional adjustability is provided for. The wheel or track structure is formed of four track members 15^d, each having an annular rib or flange 15^e. The ribs 15^e overlap each other as shown and are bolted or otherwise secured together. The ribs may have elongated slots formed thereon for the bolts whereby the track

members of each side may be adjusted toward or away from the members of the other side. Here also washers or other spacers may be placed between the ribs.

5 In the form illustrated in Fig. 13 a slightly different cross section of track member 15^f, is shown. This form may also be made from strips of metal rolled out and the ends secured together.

10 In Fig. 14, I have illustrated a circular metal ring 32 insulated from the track members 15^g, which ring 32 may act as a third rail, in case it is desired to employ an electrically driven motor vehicle in place of a 15 spring motor driven one.

More or less variation of the exact details of construction is possible without departing from the spirit of this invention; I desire, therefore, not to limit myself to the 20 exact form of the construction shown and described, but intend, in the following claims, to point out all of the invention disclosed herein.

I claim as new, and desire to secure by 25 Letters Patent:

1. In an endless track toy, a track structure comprising two annular track members, each formed with marginal annular flanges that serve as rails for a motor driven vehicle, said track members being spaced apart and set back to back and secured together, whereby the opposite flanges of the two track members form internal and external annular tracks, upon which said vehicle may 35 travel.

2. In an endless track toy, a track structure comprising annular companion track members, formed with marginal annular flanges that serve as rails for a motor driven 40 vehicle, and also formed with offset portions that serve to space one rail of a pair from the other one of the pair.

3. In an endless track toy, a track structure comprising two annular companion track members, each formed with annular marginal flanges that serve as rails for a motor driven vehicle, and also formed with offset portions that serve to space the rails of one pair from those of the other pair. 45

50 4. In an endless track toy, a track structure comprising two similar, annular companion track members, set back to back, each formed with two annular marginal flanges that serve as rails for a motor driven vehicle, and also formed with struck up spacers that are secured together.

55 5. In an endless track toy, a track member comprising an annular web portion formed with inner and outer marginal flanges on one side, and formed with offset

spacing struts on the side opposite the one from which the flanges project.

6. In an endless track toy, a supporting member having a spindle secured therein, an endless track wheel structure journaled 65 on said spindle and having two track members formed with four annular flanges that serve as internal and external rails, and as rails on the sides of the wheel structure, whereby a wheeled toy vehicle may travel 70 on any of said four sets of tracks.

7. In an endless track toy, a supporting member having a spindle secured therein, an endless track wheel structure journaled 75 on said spindle and having two track members formed with four annular flanges that serve as internal and external rails, and as rails on the sides of the wheel structure, whereby a wheeled toy vehicle may travel 80 on any of said four sets of tracks, and a stop pin arranged to be inserted in said supporting member, in position to hold the vehicle stationary on top of the wheeled structure.

8. In an endless track toy, a supporting 85 member having a spindle secured therein, and capable of standing upright or lying down, an endless track wheel structure journaled on said spindle and having two track members formed with four annular flanges 90 that serve as internal and external rails, and as rails on the sides of the wheel structure, whereby a wheeled toy vehicle may travel on any of said four sets of tracks, and a stop pin arranged to be inserted in said 95 supporting member in position to hold the vehicle stationary on the wheel structure, or to hold the wheel structure stationary.

9. In an endless track toy, a supporting member having a spindle secured therein, an 100 endless track wheel structure journaled on said spindle and having two track members formed with four annular flanges that serve as internal and external rails, and as rails on the sides of the wheel structure, 105 whereby a wheeled toy vehicle may travel on any of said four sets of tracks, and a vehicle support, cooperating with the supporting member to hold the vehicle inverted with its wheels in contact with the internal 110 track.

10. In an endless track toy, a wheel structure formed of two similar, annular track members each struck up with inner and outer marginal flanges, and with spacing 115 struts, each capable of serving as an endless track for a wheeled toy, and both, when set back to back and secured together, serving as four endless tracks for a wheeled toy.

GUY F. JONTZ.
